FIG. 4

FIG. 1 is a front elevational view of a combined transceiver and radio, showing my new design;

FIG. 2 is a top plan view thereof;

FIG. 3 is a rear elevational view thereof;

FIG. 4 is a bottom plan view thereof;

FIG. 5 is an end view thereof, seen from the right of FIG. 1; and

FIG. 6 is an end view thereof, seen from the left of FIG. 1.

I claim:

The ornamental design for a combined transceiver and radio, as shown.
